CIGAR LIGHTER

Herbert G. Lehmann, Wood-Ridge, N. J., assignor
to Automatic Devices Corporation, Bridgeport,
Conn., a corporation of Connecticut

Application October 11, 1939, Serial No. 298,910

17 Claims. (Cl. 219—32)

This invention relates to cigar lighters, and, more particularly, to the cigar lighters of the type wherein the energization of the cigar lighter is controlled by the heating of the heating element to predetermined desired heat.

In prior constructions of cigar lighters, it has been proposed to use heat-controlled latching elements or the like for holding the igniting unit in a position on the holding device wherein the circuit is completed to the heating element.

Upon the heating element reaching a predetermined desired heat, the heat-controlled means causes the latches to release the igniting unit whereupon the circuit to the heating element is opened.

These detent members or latches must be sensitive enough to be accurately controlled by the heat-responsive member and yet sturdy enough to hold the heating element in closed-circuit position, especially where the device is to be mounted in an automobile or the like which is subject to jars and vibrations. To reach this critical condition and balance, careful adjustments must be made which greatly increase the cost of the device.

Efforts have been made to overcome this difficulty by providing magnetic coils for holding the circuit closed. These, too, were costly inasmuch as it required an additional element for this purpose.

An object of the invention is to provide a cigar lighter in which the heating element is utilized as a means for holding the circuit closed until it has reached a predetermined temperature, at which time the circuit is opened.

This is accomplished, according to the present invention, by providing the igniting unit with a pole piece which is associated with the turns of the heating coil in such a manner that, when the igniting unit or a portion thereof is moved to close the circuit to the heating element and current flows therein, a magnetizing force will be set up in the pole piece due to the current passing through the turns of the heating coil to hold the igniting unit or portion thereof in closed-circuit position. This magnetic attraction will be sufficient to maintain the circuit closed until the heating element has reached a predetermined heat whereupon a normally closed, separate switch opens the circuit through the heating element, thus releasing the magnetic force produced by the heating element, and the circuit will be also opened by movement of the igniting unit or a portion thereof.

In one form of the invention, the pole piece

is made in the shape of a cup, and the turns of the coil are disposed within the cup so as to form a magnetic field to energize the pole piece.

In another form of the invention, the pole piece is substantially U-shaped, with the heating coil wound around the bow of the U and supplying magnetizing force to the pole piece when the current passes therethrough.

It will be seen, therefore, that the heating coil, in both forms of the invention, serves a dual function, namely, supplying the means for igniting the cigar, and, at the same time, the force for holding the igniting unit in closed-circuit position.

15 In the preferred form of the invention, the heat-responsive switch for opening the circuit when the heating element reaches a predetermined heat is carried by the base contact and opens the circuit to the base contact.

20 When it is desired to obtain a second light after the heat-responsive switch has been heated to open the circuit and is still hot enough to be in open-circuit position, the present invention provides a means for reclosing the circuit.

25 This is accomplished by yieldably mounting the base contact in the holding device so that, upon manual pressure of the igniting unit against the base contact, it will move the base contact into engagement with the auxiliary contacts which

30 bridge the heat-responsive contact, and will enable the circuit to be reestablished around the heat-responsive switch to the heating element irrespectively and independently of the condition of the heat-responsive contacts.

35 As soon as the circuit has been opened by the heat-responsive switch, the magnetic force for holding the contacts in engagement is released and the igniting unit is moved in the holder by an urging means so as to open the circuit between these contacts.

40 To prevent the moving means from projecting the igniting unit from the holder upon the release of the magnetic holding means, the present invention provides a detent on the holder which

45 will engage an abutment on the igniting unit and hold it in normal open-circuit position, but which will yield to permit the igniting unit to be removed for use.

Other features and advantages will be apparent from the specification and claims when taken in connection with the drawing, in which:

Figure 1 shows the holding device partly in section with the igniting unit in normal open-circuit position.

Fig. 2 is a longitudinal sectional view of the

holder and igniting unit showing the igniting unit in closed-circuit position.

Fig. 3 is a longitudinal sectional view of the holder and igniting unit showing the contact bridging the heat-responsive switch means.

Fig. 4 is a sectional view, taken along line 4—4 of Fig. 1.

Fig. 5 is an end view of another form of heating coil.

Fig. 6 is a sectional view, taken along line 6—6 of Fig. 5.

According to the present invention, the holding device or holder 10 comprises a metal tube 11 adapted to be mounted in an aperture 12 in the dashboard of an automobile or other suitable support which is grounded.

The holding device is provided with a plurality of lanced-out tangs 14 which are adapted to engage the rear surface of the dashboard or support and be drawn into clamping relation by an escutcheon plate 15 threaded on the end of the metal tube which projects through the opening.

The other end of the holding device is provided with a transversely extending end wall 16 having an aperture at its center in which is positioned a sleeve 18 having a flange 19 extending in an overlapped relation with the end wall and insulated therefrom by a washer 20.

The sleeve is insulated from the end wall by means of an insulating bushing 21, and is locked in place by means of a nut 22 threaded on the outer surface of the sleeve. The sleeve is adapted to be connected to a suitable source of energy, such as the battery of an automobile, by means of a connector lug 23 disposed therearound, and having a conductor secured thereto. The connector lug is secured to the sleeve by means of a nut 25 which is turned up to clamp the connector against the nut 22.

As shown in the drawing, the holding device has a contact disk 27 in the end thereof to be engaged by an igniting unit contact as will be explained. In the preferred form of the invention, the contact is mounted on a plunger 28 consisting of a sleeve 29 slidably mounted in the sleeve 18 and having a shoulder 29a abutting the end of the sleeve 18, as is clearly shown in Fig. 2, to limit its forward movement.

The other end of the sleeve has a switch arm 30 in electrical engagement therewith and projecting outwardly therefrom. At the outer end of the arm is a contact 31. The contact, as shown in Fig. 2, is threadedly mounted in the switch arm so that its position can be adjusted with respect thereto to alter the operation of the switch.

A cooperating contact 32 is carried by a heat-responsive means, preferably a bimetallic arm 33, which extends into juxtaposition with the switch arm, but is insulated therefrom by an insulating washer 33a. By suitably adjusting the position of contact 31, the temperature at which the switch will open can be controlled.

The base contact is in engagement with the bimetallic arm and the whole plunger assembly is locked together by a bolt 34 having its head 35 disposed in a recess at the center of the contact 27, as shown in Fig. 2, with the bolt extending through an insulating tube 36 carried by the sleeve 29 to insulate the bolt therefrom. The bolt is drawn into clamping relation by means of a nut threaded on the end thereof, but insulated from the shoulder 29a by suitable insulation as shown.

A U-shaped spring contact member 38 is dis-

posed between the flange 19 of the sleeve 18 which is connected to the source of energy and the switch arm 30, in such a manner that the bow in the U normally engages the switch arm 30 and yieldingly urges the plunger assembly and contact forwardly in the holding device to the position shown in Figs. 1 and 2. The ends of the U, as shown at 38a in Fig. 1, are normally held out of engagement with the contact disks due to the positioning of the disk by the bow of the spring. In this position, the circuit from sleeve 18 to the contact 27 must pass through the heat-responsive switch.

The sleeve 18, as shown in Fig. 2, is provided with a slot 43 in which a pin 44 carried by the sleeve 29 is positioned, and prevents rotation between the elements and which limits the relative movement between these elements when the spring 38 is compressed as will be explained.

The igniting unit of the present invention comprises an insulating sleeve 50, having a portion 51 thereof of reduced diameter, and threaded at 52 to receive a handle 53, whereby the igniting unit can be gripped and manipulated. The other end of the sleeve is provided with an internally threaded cavity 54 into which a heating element unit 55 of the present invention is mounted.

As shown in Figs. 2 and 3, the heating unit comprises a cup-shaped member 56 of magnetic material having a helical coil 57 of resistance wire disposed therein, one end 57a of the coil being anchored to a central stud 58 which forms one contact for the heating element. The other end 57b of the heating coil is positioned between 35 a conducting cap 59 and insulating washer 60 so as to be electrically connected with the conducting cap.

A nut 61 is threaded on the central stud which passes through the cup and the conducting cap and clamps the heating element and the insulating washers in place on the conducting cap so as to form a replaceable heating element unit.

The conducting cap is connected by a wire 62 to a ring 63 clamped under the handle and connects the other end of the heating coil to the handle which is of metal and forms a part of the heating coil circuit.

When in the normal inoperative or carrying position as shown in Fig. 1, the igniting unit is disposed in the holding device with the heating element contact held out of engagement with the base contact by means of a friction sleeve 65 having an outturned flange 66 at its forward end engaging the escutcheon plate of the holding device so as to limit its inward movement and having at its inner end an inturned flange 67 which surrounds the reduced portion of the insulating sleeve and urged into engagement with an abutment 68 on the igniting unit by a spring 69 disposed between the inturned flange and the end of the handle which is threaded to the reduced portion of the sleeve.

The spring also connects the metal handle to the grounded dashboard through the friction sleeve and thus completes a portion of the electrical circuit for the heating element.

When it is desired to energize the heating element, manual pressure is applied to the handle and the spring will yield to permit the heating element contact to be moved into engagement with the disk contact, and close the circuit to the heating element. This circuit will then be from the battery, through the connector lug, to sleeve 18, through the sleeve 18, spring 38 and

sleeve 29, switch arm 30, contacts 31, 32, bimetallic arm 33, to the contact disk 27, through the heating element contact 58, through the heating coil 57, to the conducting cap 59, through the wire conductor 62, to the handle 53, through the spring 69, and friction sleeve 65, to the holder 10 and thus to ground.

As soon as the circuit is established, current passing through the heating coil will produce a magnetic field and set up a magnetic force in the pole piece 56 which will hold it in engagement with the disk contact 27 and maintain the igniting unit in the position shown in Fig. 2 against the urging of the spring 69.

As the heating element is heated up, the bimetallic arm 33 will become heated and will flex to the dotted position shown in Fig. 2 to move contact 32 from contact 31 and open the circuit to the heating coil. The contact disk 27 may be cut away, as shown at 70 in Fig. 4, to permit the arm to flex more readily.

As soon as the circuit is opened at the auxiliary switch contacts 31, 32, current will no longer flow in the heating coil, and the magnetic force produced in the pole piece will be reduced so that the spring 69 can move the igniting unit outwardly of the holder and separate the heating element contact from the base contact, thus opening the circuit at this point until it is again manually closed.

In order to prevent the spring from ejecting the igniting unit out of the holding device when the magnetic force is released, the present invention provides a spring finger 71 lanced inwardly from the holding device. The conducting cap extends around the outside of the insulating sleeve to form an abutment 72 thereon which will be engaged by the spring finger, as shown in Fig. 1, to limit the outward movement of the igniting unit to its normal position.

The spring finger can be readily overcome by the normal pressure utilized in removing the igniting unit for use and replacing it in the holder.

When it is desired to energize the heating coil to obtain a second light before the heat-responsive bimetallic contact arm 33 has cooled sufficiently to position the contacts 31 and 32 in engagement, the present invention provides an auxiliary circuit which will shunt out the switch upon manually pressing the igniting unit into engagement with the base contact and applying an additional pressure thereto. This will cause the U-shaped spring 38 disposed between the contact arm 30 and the flange 19 to be compressed so that it assumes a position, as shown in Fig. 3, wherein the ends 38a of the spring arm bridge the gap between the flange 19 and the contact plate 27, thus shorting out the switch contacts 31, 32 and providing a direct contact to the contact plate from the sleeve 18.

To indicate when the heating element has attained the desired incandescence and prevent overheating of the heating element when the heat-responsive switch is thus shunted out, the present invention provides suitable apertures 75 in the heating element unit through which light from the incandescent heating element is transmitted to a lens 76 mounted in the handle.

In the form of the invention of the heating element unit shown in Figs. 5 and 6, the pole piece comprises a U-shaped member 156 of metallic, magnetic material, and the heating element coil 157 is wrapped around the pole piece as shown in Fig. 6 and insulated therefrom.

One end 157a of the coil is electrically connected to the pole piece 156 which forms the heating element contact, and the other end is electrically connected to the conducting cap 159.

5 The unit is mechanically clamped together by a central stud 158 connected to the pole piece and passing through the unit and having a nut 161 threaded on the end thereof.

The heating element unit of this form of the 10 invention is mounted on the igniting unit as in the first form, and when energized the pole piece 156 cooperates with the base contact to hold the igniting unit in closed-circuit position.

In the broader aspects, it will be seen, therefore, that the use of critical latches may be eliminated and the heating coil utilized to serve two functions, namely, to provide the means for holding the circuit closed and to also function as the means for igniting the cigar or cigarette.

15 Variations and modifications may be made within the scope of this invention and portions of the improvements may be used without others.

I claim:

1. In an electric cigar lighter, a base contact; 25 an igniting unit mounted on a holding device and having a heating element comprising a coil of resistance wire; a contact connected to the heating element and adapted to close a circuit thereto upon engagement with the base contact; means for urging said heating element contact into open-circuit position; means carried by the igniting unit and magnetized by the field produced by passage of current through the coil of the heating element, said means being operative 30 upon magnetization to hold the heating element contact in engagement with the base contact; and automatic means to break the energizing circuit independently of the contacts upon the heating element attaining a predetermined desired 35 heat, said means also interrupting the excitation of said magnetic means and thereby releasing said heating element contact for disengagement by said urging means from said base contact whereby the circuit is also opened at said contacts.

2. In an electric cigar lighter, a holding device 40 having a base contact; an igniting unit having a heating element thereon comprising a coil of resistance wire; a contact connected to the heating element; means for urging the heating element contact into open-circuit position; means for moving the heating element contact against the urging means into contact with the base contact to energize the heating element; means magnetized by the field produced by passage of current through the coil of the heating element, said means being operative upon magnetization to hold the heating element contact in engagement with the base contact; and automatic 45 means to open the circuit upon the heating element attaining the desired heat, excitation of said magnetic holding means being interrupted upon the current ceasing to flow through the heating element, the heating element contact being released thereby for movement by said urging means into open-circuit position.

3. In an electric cigar lighter, a holding device 50 having a base contact; an igniting unit having a heating element thereon comprising a coil of resistance wire; a contact connected to the heating element and carried by the igniting unit; means for urging the igniting unit into open-circuit position; means for closing the circuit to the heating element upon movement of the igniting unit and the contact carried thereby.

against the urging means into engagement with the base contact; means carried by the igniting unit and magnetized by the current passing through the heating coil to hold the igniting unit in closed-circuit position; heat-responsive means for opening the circuit and releasing the magnetic hold when the heating element attains a predetermined heat; and a detent means for preventing the urging means from moving the igniting unit out of the holding device upon release 10

4. In an electric cigar lighter, a holding device; an igniting unit mounted on the holding device and completely removable therefrom for use; a coiled heating element carried by the igniting unit; an electric circuit for energizing said heating element; means for closing said circuit upon motion of said igniting unit relative to said holding device; means for urging said igniting unit to open-circuit position; magnet means energized by the field produced by the passage of current through the coils of the heating element, said means being operative upon magnetization to hold the circuit closed; and means for automatically interrupting said circuit independently of the position of the igniting unit on the holding device upon said heating element reaching a predetermined desired heat, whereby said magnet means is deenergized and said igniting unit released thereby for movement by the urging means to open-circuit position.

5. In a cigar lighter, a removable igniting unit having an igniting coil; a holding device having a base contact of magnetic material movably mounted thereon to cooperate with a magnet operated by the heating coil of said removable igniting unit to maintain a circuit closed to the heating coil thereof; heat-responsive contacts carried by the base for opening the circuit to the base contact and heating coil upon the heating coil attaining a predetermined heat whereupon the magnet releases its attraction for the base contact; and means for closing the circuit responsive to movement of the base contact on the holding device and independently of the heat-responsive contacts.

6. In a cigar lighter, a removable igniting unit, a heating coil carried thereby; a holding device having a base contact slidably mounted therein; means for urging said contact to a position to be engaged by a contact of said removable igniting unit to complete a circuit to the heating coil carried thereby; magnetic means for holding the igniting unit in engagement with the base contact to close the circuit to the heating element; heat-responsive contacts carried by the base contact for connecting the base contact to a source of energy, said contacts opening the circuit to the base contact, magnetic means, and heating coil upon the heating coil attaining a predetermined heat; and means for bridging the heat-responsive contacts upon sliding the base contact against the urging means in response to an externally applied force, whereby the base contact can be connected to the source of energy independently of the heat-responsive contacts, said urging means breaking the independent connection of the base contact to the source of energy and reestablishing control by the heat-responsive contacts of the base contact circuit upon release of said externally applied force.

7. In a cigar lighter, a removable igniting unit; a heating coil carried thereby; a holding device having a sleeve of conducting material insulatedly mounted in one end thereof, said sleeve being 75

adapted to be connected to a source of energy; a plunger having a base contact insulatedly secured thereon slidably mounted in the sleeve; means for urging the base contact into a position 5 to be engaged by a contact of said removable igniting unit to complete a circuit to the heating coil carried by the igniting unit; heat-responsive contact means carried by the plunger for connecting the base contact to the sleeve, said contact means opening the circuit to the base contact and heating coil upon the heating coil attaining a predetermined heat; and auxiliary contact means connected to the sleeve and engaging the base contact for bridging the heat-responsive contact means upon movement of the base contact against the urging means whereby the base contact can be connected to the source of energy independently of the heat-responsive contacts.

8. In an electric cigar lighter, a holding device; a yieldably mounted contact positioned in the base of the holding device; an igniting unit mounted on the holding device and having a heating coil thereon; means carried by the igniting unit and magnetized by current passing through the heating coil for holding the igniting unit in closed-circuit position with the yieldably mounted contact in the base; heat-responsive switch means carried by the yieldably mounted contact for opening the circuit to the heating coil when the heating coil attains a predetermined heat to remove the magnetizing force; and means for remaking the circuit to the heating coil upon sliding the yieldable base contact to close a second circuit thereto independent of the heat-responsive contact.

9. In a cigar lighter, a holding device having a contact in the base thereof; yieldable mounting means for said contact; an igniting unit having a heating element thereon comprising a coil of resistance wire; means for closing the circuit to the base contact upon manual movement of the igniting unit into engagement with the base contact; magnetic means for holding the igniting unit in engagement with the base contact to close the circuit to the heating element; heat-responsive switch means for opening the circuit to the base contact and said magnetic holding means upon the heating element attaining a predetermined desired heat; and means operable 40 upon manually pressing the igniting unit against the base contact to move the base contact against its yielding mounting to bridge the heat-responsive switch means independently of the condition thereof, whereupon reenergization of the heating element can be obtained, said yieldable mounting reestablishing the control by said heat-responsive switch means of the base contact circuit upon releasing the manual pressure on said igniting unit.

10. The combination of a holding device, an igniting unit adapted to be movably held by said holding device comprising a body of insulating material having a handle at one end and a heating coil at the other end thereof, and a pole piece 65 of magnetic material associated with the heating coil and rendered operative to hold the igniting unit in closed-circuit position on the holding device by current passing through the heating coil.

11. The combination of a holding device, an igniting unit adapted to be movably held by said holding device comprising a body of insulating material having a handle at one end and a heating coil at the other end thereof having a plu-

rality of turns of resistance wire, and a cup-shaped pole piece of magnetic material associated with the heating coil and rendered operative by current passing through the turns of the heating coil to hold the igniting unit in closed-circuit position.

12. The combination of a holding device, an igniting unit adapted to be movably held by said holding device comprising a body of insulating material having a handle at one end and a heating coil at the other end thereof having a plurality of turns of resistance wire, and a U-shaped pole piece of magnetic material having the turns of the heating coil wound around the bow of the U and rendered operative by current passing through the turns of the heating coil to hold the igniting unit in closed-circuit position.

13. A heating element unit for use on an igniting unit adapted to be removably carried by a holding device, comprising a support secured to the igniting unit; a pole piece secured to the support; and a heating coil mounted on the support and associated with the pole piece and operative to magnetize the pole piece upon passage of current through the heating element.

14. A heating element unit for use on an igniting unit adapted to be removably carried by a holding device, comprising a support of conducting material to be threaded to the igniting unit; a cup-shaped pole-piece secured to the support; and a heating coil having a plurality of turns of resistance wire mounted on the support and associated with the pole piece so as to be operative to magnetize the pole piece upon passage of current through the heating element.

15. A heating element unit for use on an igniting unit adapted to be removably carried by a holding device, comprising a support of conducting material to be threaded to the igniting unit; a U-shaped pole piece secured to the support; and a heating coil wound around the bow of the U so as to be operative to magnetize the pole

piece upon passage of current through the heating element.

16. In an electric cigar lighter having a holding device, and an igniting unit, including an electric heating element, mounted on said holding device and completely removable therefrom for use, a circuit for energizing said heating element; circuit control means for closing said circuit and normally urged to open-circuit position; electromagnetic means energized by the field produced by the current passing through said heating element upon closure of said circuit, the magnetic field produced by said energization operating as the sole means for holding said circuit control means in closed-circuit position; and automatic heat-responsive means, independent of said circuit control means, for automatically interrupting said circuit upon said heating element attaining a predetermined useful temperature, interruption of said circuit rendering said electromagnetic means inoperative and thereby releasing said circuit control means to open said circuit.

17. In an electric cigar lighter, an igniting unit mounted on a holding device and completely removable therefrom for use; an electric heating coil on said igniting unit; a normally open circuit for energizing said electric heating coil; circuit control means for closing said circuit and normally urged to open-circuit position; magnet means energized by the field produced by the passage of current through said heating element coil, and operative upon energization to hold said circuit control means in closed-circuit position; and automatic means for interrupting said circuit, independently of said circuit control means, upon said heating element attaining a predetermined useful temperature, interruption of said circuit deenergizing said magnet means and thereby releasing said circuit control means for return to its normal open-circuit position.

HERBERT G. LEHMANN.
